UNITED STATES PATENT OFFICE.

HARRY G. ALDRIDGE, OF ROCHESTER, NEW YORK.

CLOSURE FOR MILK BOTTLES OR JARS.

1,157,282.

Specification of Letters Patent. Patented Oct. 19, 1915.

Application filed September 15, 1914. Serial No. 861,796.

To all whom it may concern:

Be it known that I, HARRY G. ALDRIDGE, of Rochester, in the county of Monroe and State of New York, have invented a new and useful Improvement in Closures for Milk Bottles or Jars, which improvement is fully set forth in the following specification and shown in the accompanying drawings.

The present invention relates to closures for milk jars and similar receptacles, an object of the invention being to provide a closure which may be readily opened to permit the milk to be discharged without removing the closure from the jar or bottle.

Another object of the invention is to provide a discharging closure for milk bottles made from a single piece of paper stock without the provision of any separate fastening devices.

To these and other ends, the invention consists in certain parts and combinations of parts all of which will be hereinafter described, the novel features being pointed out in the appended claims.

In the drawings: Figure 1 shows a common milk jar in vertical section with the improved closure attached thereto in closed position, the closure also being shown in section; Fig. 2 is a view similar to Fig. 1 showing the cover of the closure open; Fig. 3 shows the two disks of the closure before being folded one upon the other; Fig. 4 is a plan view of a closure with the two disks folded one upon the other; and Fig. 5 shows the closure with the hinged portion of the upper disk raised.

Referring more particularly to the drawings, 1 indicates an ordinary milk jar or bottle which has its mouth provided with an internal groove for receiving a closure. In this instance, the closure embodies a member or disk 2 provided with a discharge opening 3, the latter preferably being entirely surrounded by the stock of the disk 4 which may be paper, paper board, or any other desired material. To provide a spout for the discharge opening, the latter may have one edge formed with a curved tongue 4 which is separated from the body portion 5 of the disk 2 by a curved score line permitting the tongue to be bent easily to the position shown in Fig. 2 by the finger of the user, the tongue normally lying in the plane of the disk 2.

In order to provide a cover for the discharge opening, a second disk may be em-

ployed, which like the first-named disk is of circular form of substantially the same diameter as said first-named disk, although in practice, I prefer to make this second disk of slightly smaller diameter than the first-named disk, permitting the second disk to be removed more readily from the groove in the neck of the jar than the first-named disk so that its function as a cover will not be interfered with. This second disk is preferably made in one piece with the first-named disk and to this end the peripheries of the disk are connected at 6 by a short neck which readily permits one disk to be folded upon the other. This second disk preferably embodies two portions 7 and 8 separated by a scoring 9 which permits the member 8 to swing relatively to the member 7 in order to cover and uncover the discharge opening 3. A lateral lifting projection 10 connected to the portion 8 by scoring 11 lies at one side of a central line through both of the disks when the latter are in the same plane as shown in Fig. 3, this arrangement being provided in order that additional stock will not be required for the formation of this projection but that the otherwise wasted stock may be utilized.

A closure according to this invention is simple to manufacture and easy to operate. The two disks are formed simultaneously in connected relation so that all assembling is unnecessary and fastening devices are dispensed with. The disks are readily folded into superposed relation and can be easily fitted into the mouth of a jar. The cover portion of the upper disk can be easily moved to uncover the dispensing opening in the lower disk without disturbing the position of the lower disk within the neck of the jar, the movement of the cover being facilitated by the integral tongue or projection which may be grasped with ease by the user. The closure enables the milk bottle to be used for dispensing the milk therefrom while, at the same time, retaining the closure in the neck of the bottle.

What I claim as my invention and desire to secure by Letters Patent is:

1. A closure for milk bottles comprising a circular disk having a discharge opening entirely surrounded by the material of the disk and also having a spout-forming portion cut from the material of the stock at one edge of the discharge opening, the spout-forming portion being separated from

the remaining portion of the disk by a score so that it may be bent outwardly from the plane of the disk.

2. A closure for milk bottles comprising two circular disks formed from a single blank and folded one upon another, one of said disks being provided with a discharge opening and the other of said disks closing said opening and being provided with a score extending from one edge thereof to another to permit a portion of said disk to swing to open and close the opening, said scored disk being slightly smaller in diameter than the one with the opening and the swinging portion of the scored disk being wider than the other portion.

3. A closure for milk bottles comprising two circular disks formed from one piece of material and folded one upon the other, one of said disks being provided with an opening entirely surrounded by the material

and the other of said disks having a transverse score permitting a portion thereof to bend relatively to the other portion to act as a cover for the opening, the swinging portion of the scored disk being wider than the other portion.

4. A closure for milk bottles comprising two circular disks formed from one piece of material and folded one upon the other at one side thereof, one of said disks being provided with a discharge opening and the other of said disks being provided with a transverse score at an angle to the fold and also with a tongue to one side of a central line through the two disks before they are folded.
